PALLET

Lawrence Skendrovic, West Mifflin, Pa., assignor to
Pallet Development, Inc., Ambridge, Pa.

Filed Dec. 14, 1971, Ser. No. 208,051

Term of patent 14 years

Int. Cl. D12—99

U.S. Cl. D14—3

The figure is an isometric view of a pallet showing my new design, it being understood that the bottom and two sides not shown are the same as the top and sides shown.

Since opposite ends and opposite sides of the pallet exactly correspond, one view fully discloses the construction.

I claim:

The ornamental design for a pallet, as shown and described.
